BARREL STRUCTURE

Edward H. Little and William R. Vansant,
Ashland, Ky.

Application May 10, 1938, Serial No. 207,142

3 Claims. (Cl. 217—3)

This invention relates to barrel structures and more particularly to whiskey barrels which are charred on the inner surfaces of the staves.

An object of the present invention is to provide a whiskey barrel having an inner lining of separate charred staves and means for removably clamping the same in the barrel to the end that defective staves in the lining may be readily replaced.

10 A further object of the invention is to provide a charred stave inner lining which may be applied to barrels now in use as well as to barrels in the course of construction without alterations to the barrel.

15 With the above and other objects in view the invention consists of certain novel details of construction and combinations of parts hereinafter fully described and claimed, it being understood that various modifications may be resorted to 20 within the scope of the appended claims without departing from the spirit or sacrificing any of the advantages of the invention.

In the accompanying drawing forming part of this specification,

25 Figure 1 is a longitudinal sectional view of a barrel equipped with a lining of charred staves removably clamped in position, in accordance with the invention.

Figure 2 is a cross sectional view taken on the 30 line 2—2 of Figure 1 and showing the two sections of the clamp held in place by wedges.

Figure 3 is a detail perspective view of one of the wedges.

Figure 4 is a plan view of one of the sections of 35 the clamp.

Referring now to the drawing in which like characters of reference designate similar parts in the various views, 10 designates a conventional whiskey barrel. To form a charred inner surface 40 for the barrel the present invention provides a plurality of staves 11 which are charred on one surface or both surfaces as desired. The staves are removably held in place at the ends by the heads 12 of the barrel and are removably held 45 in place at the center through the medium of a two-piece clamp.

The two-piece clamp comprises a pair of companion sections 13, one of which is shown in Figure 4, each section being in the form of substantially one-half a disc and formed of the same material as the staves. Both faces of the section are charred. Opposite the curved edge the section is provided with a pair of converging cam edges 14. The sections 13 are fitted into the 55 barrel with their curved edges against the staves

and with their converging cam edges 14 disposed opposite each other near the center of the barrel. A pair of wedges 15 are then applied to the cam edges of the sections 13. Each wedge is provided in its opposite sides with grooves 16, 5 as best shown in Figure 3, to receive the opposite cam edges 14 of the clamp sections 13. The wedges are disposed with their smaller ends directed toward the staves. Both wedges are driven on the sections in a direction away from 10 the center of the barrel to wedge the sections of the clamp tightly against the inner surfaces of the staves 11. All faces of the wedges are charred.

To replace defective staves of the inner lining 15 it is simply necessary to drive the wedges 15 toward each other to release the sections 13 of the clamp from engagement with the staves, after one head of the barrel has been removed. Thereupon the separate staves may be readily inspected and defective staves replaced with new charred staves.

From the above description it is thought that the construction and operation of the invention will be fully understood without further explanation.

What is claimed is:

1. The combination with a whiskey barrel, of an inner lining of charred staves, charred substantially semi-circular clamp sections disposed 30 transversely of the barrel and removably clamping the lining staves against the inner surfaces of the staves of the whiskey barrel, and wedge means removably securing the clamp sections against the staves.

2. The combination with a whiskey barrel, of a plurality of charred staves lining the inner surfaces of the barrel staves, a pair of oppositely disposed substantially semi-circular clamp sections disposed transversely in the barrel at the 40 center of the barrel and having opposed cam edges, and a pair of wedges engaged between the sections of the clamp and forcing the sections tightly against the centers of the charred staves to removably hold the charred staves in position.

3. The combination with a whiskey barrel, of an inner lining comprising charred staves extending throughout the entire inner surfaces of the staves of the barrel, said charred staves extending to the heads of the barrel and being confined at the ends in the barrel by said heads, oppositely disposed clamp sections of substantially semi-circular outline having curved edges 50 engaging the inner faces of the staves at about 55

the center thereof and having oppositely disposed inclined converging cam edges opposite the curved edges, and a pair of wedges having grooves in their sides receiving the cam edges of the clamp section, said wedges having their small end directed to the charred staves, said wedges

being driven outwardly from the center of the barrel on the clamp sections to wedge the sections of the clamp tightly in place.

EDWARD H. LITTLE.
WILLIAM R. VANSANT.
